DESIGN FOR A COMBINED DISPLAY RACK AND HOLDER, FOR BROOMS, MOPS, OR THE LIKE

Clarence S. Anderson, Des Moines, Iowa, assignor
to New Monarch Machine & Stamping Co., Des
Moines, Iowa

Application July 15, 1940, Serial No. 93,659

Term of patent 3½ years

To all whom it may concern:

Be it known that I, Clarence S. Anderson, a citizen of the United States and resident of Des Moines, Polk County, Iowa, have invented a new, original and ornamental Design for a Combined Display Rack and Holder, for Brooms, Mops, or the like, of which the following is a specification, reference being had to the accompanying drawing, forming a part thereof.

Fig. 1 is a front perspective view of a combined

display rack and holder, for brooms, mops, or the like, showing my design.

Fig. 2 is an end elevational view; and
Fig. 3 is a front elevational view thereof.

I claim:

The ornamental design for a combined display rack and holder, for brooms, mops, or the like, substantially as shown.

CLARENCE S. ANDERSON.
